CONCEALING SIDING PANEL JOINT

Erving M. Young, East Orange, N. J., assignor to
 The Patent and Licensing Corporation, New
 York, N. Y., a corporation of Massachusetts

Application March 27, 1945, Serial No. 585,049

5 Claims. (Cl. 20—5)

1

This invention relates to building siding material having a rigid, fibrous panel base and an impressed or embossed face which simulates masonry, such as brick work and intervening mortar joints. More particularly, this invention is concerned with the problem of concealing the joints between assembled panel units of the foregoing type having the masonry-simulating areas thereof surfaced with mineral particles or granules of one color, and the mortar joint-simulating areas thereof surfaced with mineral particles or granules of a different or blending color.

Heretofore, it has been difficult with siding panels of the above character effectively to conceal the actual joints between the assembled panels so as to achieve an appearance which closely simulates masonry or the like. These panels are commonly formed of rigid, fibre composition board which is surface impregnated with bituminous material, such as asphalt, coated with a waterproof asphaltic coating on the face thereof to be exposed, this coating being surfaced with mineral granules or particles of brick color applied to the brick-simulating areas and of contrasting color applied to the mortar joint-simulating areas. When such panels are applied to a building in interfitted, coplanar relation, it is impossible, as a practical matter, to obtain such uniform abutment of the edges of adjacent panels as will entirely conceal the joint lines or crevices between the panels. This failure is due particularly to irregularities in the cutting of the panels which prevents the desired erected relation therebetween, or to carelessness in their erection.

Actually, it is extremely difficult, if not impossible, in the manufacture of the composition board to obtain the exact sizes desired. The minimum tolerances to which board manufacturers can ordinarily work are about $\frac{1}{16}$ " at each edge. Consequently, the horizontal edges of adjacent finished panels do not fit tightly together when applied in assembled relation to one another and the horizontal crevices occurring at the joints between these panels, even when skillfully applied, being of dark color, as compared to the color of the mineral granules applied to the brick-simulating areas as well as to those applied to the mortar joint-simulating areas, serve to set up the panel outline and destroy the desired illusion of an integral wall of natural masonry.

It is the primary object of the present invention to overcome the foregoing disadvantages by providing building siding panels having granules of brick color applied to the brick-simulating areas and contrastingly colored granules applied to the

2

mortar joint-simulating areas with simple and novel means along one longitudinal margin of each panel for effectively concealing the horizontal joints between adjacent assembled panels, without requiring special skill or care in their assemblage.

In accordance with the present invention, the foregoing and related objects may be attained by providing a rabbet, cutout or recess along one longitudinal margin of a rectangularly formed, ship-lapped panel blank. This recess is filled with asphaltic coating, when the latter is applied to the face of the panel that is to be exposed. The coating, particularly the portion which fills the recess, is surfaced with granular material so that there may be provided, along the longitudinal margin defined by the coating-filled recess, a rolled, compacted masonry-colored granular surface which extends substantially the entire depth of the recess slightly beyond the edge of the panel which is to abut an edge of an overlapped panel. In this manner, I effect a tight joint between the abutting panels, thereby effectively concealing any joint crevices that may be formed, unavoidably or otherwise, between said abutting panels.

Other advantages and features of the invention will become readily apparent in the following description and the accompanying drawing in which

30 Fig. 1 is a plan view of a masonry simulating siding panel;

Fig. 2 is a similar view of three such siding panels showing the manner in which they are laid in coplanar, abutting relation to form an exterior covering for a side wall;

35 Fig. 3 is an enlarged fragmentary view, in perspective, of a masonry simulating siding panel embodying the invention;

Fig. 4 is a fragmentary sectional view of vertically adjoining panels taken substantially along lines 4—4 of Fig. 2 and illustrating particularly the manner in which the present invention serves effectively to conceal the joints or crevices therebetween, and

45 Fig. 5 is a fragmentary sectional view diagrammatically illustrating the manner in which the rabbed marginal edge of a panel may be provided with an overhanging rolled, compacted masonry colored granular surface.

50 Referring to Fig. 1 of the drawings, the numeral 10 designates a panel of building siding material. This panel preferably comprises a substantially rigid base of fibre insulation board 11, generally rectangular in shape, and provided with ship-lap flanges 12 at one longitudinal and one transverse

edge thereof, while the other two edges of the panel are formed in complementary relation to the first-named edges by undercutting thereof to provide projecting ship-lap flanges 13. Thus, the upper face of the flange 13 forms a continuation of the face of the panel. These panels are adapted to be applied in abutting, coplanar relation, with the ship-lap flange 13 of one panel overlapping the complementary flange 12 of the adjoining panel, as illustrated in Figs. 2 and 4, to form a water-tight joint therebetween.

In accordance with the present invention, the panel blank 11, in addition to being properly cut to size and provided with complementary ship-lap flanges 12 and 13, as previously described, is provided with a rabbet, notch or recess 25 extending for the entire length along one longitudinal edge of the blank. As best shown in Fig. 3, this recess or rabbet 25 has its sides or faces 26 and 27 extending preferably, although not essentially, at right angles to each other.

The panel blank thus provided may then be impregnated with asphalt or other similar bituminous material in order to stiffen the board and bind the surface fibres together against delamination. The approximate extent of this surface impregnation is indicated by the stippled border areas, as at 14. The exposed face of the thus impregnated panel base is then coated with a layer of thermoplastic asphaltic coating material 15, such as high melt point asphalt, combined with suitable filler material. In addition to forming a layer of substantial thickness on the flat surface of the blank, the coating will also flow over the edge thereof and fill the recess or rabbet 25 substantially to the level of the layer on the flat surface so as to be continuous therewith. As the asphalt layer 15 cools, it becomes bonded to the surface and will be retained in the rabbet 25 so as to completely fill the latter, thus providing an additional thickness of coating along this edge of the panel base.

While the coating layer, including the vertically extending portion thereof along the filled recess, is still in a plastic, adhesive condition, it is surfaced with granular material 16 of mineral character and of suitable color to simulate conventional brick, stone or the like. These granules 16 may be partially imbedded in the coating, as by the application of suitable roll pressure. Subsequently, granular material 18 of similar character, but of a different or distinguishing color to simulate mortar, may be applied over the entire flat upper surface. The blank may then be subjected to a selective embossing operation which partially imbeds the second layer of granules only in those areas which are to simulate mortar joints, while at the same time forming uniformly spaced narrow grooves 20 to give the desired relief effect. After the second colored layer 18 has been pressed in the desired pattern, the excess granules not imbedded in the coating, particularly those covering the masonry-simulations, may be removed in any suitable manner to expose the masonry-simulating areas 17 separated and set off in relief by the differently colored mortar joint-simulating grooves 20.

In the case of brickwork, the masonry simulating areas 17 take the form of oblong-shaped formations of suitable width and length to simulate a brick arranged in horizontal rows or courses, generally five in number, and in staggered order. As shown in Fig. 1, the upper longitudinal edge of the panel is defined by a continuous horizontal mortar joint-simulation 20 and each of the suc-

ceeding rows or courses are spaced apart by a similarly extending mortar joint-simulation of uniform width. The adjacent brick-like formations 17 in each row or course are spaced apart or set off from each other by a vertical mortar joint-simulation 21. At the lower longitudinal edge of the panel, the spaced brick-like formations extend to the very edge thereof, thus defining and constituting a part of the projecting ship-lap flange 13. At the ends of the alternate rows or courses there are formed part-brick formations 17a which are of the same character, material and width as the whole-brick formations 17 but different therefrom in length. The lengths of the two end part-brick formations 17a in each of these alternate rows, when combined, are equal to the length of the individual intermediate whole-brick formations. A series of uniformly spaced narrow grooves 22, simulating wire scorings, are formed transversely on all of the part-brick formations and on some of the intermediate whole-brick formations, as shown.

When the panels are joined endwise in abutting coplanar relation, as shown in Fig. 2, the part-bricks of one panel abut against the part-bricks of the other, thus overlapping the vertical joint between the units and serving effectively to conceal said joint.

In the further practice of the present invention, the filled and granule surfaced rabbeted margin of the panel is subjected to a rolling and compacting operation preceding the aforescribed embossing operation and, preferably, immediately following the step of applying the layer of mineral granules 16 and partially imbedding this layer in the coating.

In this operation, illustrated in Fig. 5, the panel 10 may be conveyed by supporting rollers 35, or other suitable means, into contacting position 40 with a roller wheel 36 in such manner that the vertical edge 19 of the projecting ship-lap flange 13 will abut against the roller. The roller wheel 36 may be formed of wood or other suitable material and, as shown, is provided with a reduced upper portion 38, having a radius approximately $\frac{3}{2}''$ to $\frac{1}{8}''$ less than that of the lower portion and having its horizontal face 39 substantially aligned with the horizontal face 26 of the rabbet 25. The roller wheel will freely rotate about its vertical axis 37 as the edge 19 of the advancing ship-lap flange 13 of the panel is brought into contact therewith. This edge 19 serves as a firm guide to permit the periphery 40 of the reduced portion 38 to compact and shape uniformly the vertically extending granule surface 45.

The roller wheel permits the rolled, compacted and adhesively anchored granule surfaced layer to extend somewhat beyond the vertical edge 19 of the ship-lap flange 13, thus providing an overhang of say $\frac{3}{2}''$ to $\frac{1}{8}''$ depending upon the radius of the reduced portion of the wheel.

There is thus provided a simple but effective means for concealing the panel joint or crevice between two adjacent assembled panels and thus carry out the illusion of a wall of natural masonry. It will be observed with this construction that when a plurality of panels 10 are properly arranged in edge abutment and in coplanar relation, the lower overhanging longitudinal edge 45, of the projecting ship-lap flange 13, formed as above described, will be abutted against the edge 46 of the ship-lap flange 12 forming the horizontal edge of the uppermost mortar joint-simulating groove 20. The coating and the gran-

ules at the edges 45, 46 may readily be caused by slight pressure to become intermingled or interlaced with one another, thus effectively concealing any opening or crevice that may otherwise be exposed. Such an opening or crevice that unavoidably may be formed because of irregular cutting of the panel blanks or may be formed due to careless erection, as previously indicated, is shown at 48, although this showing is somewhat exaggerated for illustrative purposes.

In addition to concealing the panel character of the constituent siding material, the provision of the rabbet along the margin of the panel in accordance with the present invention possesses further advantages which may be referred to briefly. For example, the additional volume of panel coating filling the rabbet offers a measure of added protection against any possible injury or damage that may occur to this projecting marginal edge of each of the panels during storage, transportation and application. Then, too, the additional bonding surface thus afforded between the coating and the impregnated surface of the panel blank tends to lengthen the life of the panel along that critical area which is subjected to erosive action by the drainage of rain water from the surfaces of the assembled panels.

The present invention thus renders it possible to provide siding panels surfaced with different colors of mineral particles or granules arranged respectively to simulate masonry faces and separating mortar joint lines which, when applied to a building in assembled coplanar relation, produce an effect pleasing to the eye and, at the same time, present the appearance of a well simulated masonry wall.

I claim:

1. A siding member adapted to be applied to a building wall in interfitted horizontal alignment with like members, comprising a rigid base panel of rectangular configuration having a rabbeted recess extending longitudinally on the exposed face thereof along one longitudinal margin, said face including said recess being coated with a layer of asphalt and surfaced with mineral granules, the granules being of one color along narrow linear portions simulating mortar joints and being of a contrasting color along spaced areas simulating bricks arranged in horizontal rows in staggered order, the spaced brick formations in the row immediately adjacent said longitudinal margin each having said surfaced coating layer thereon extending into and filling the rabbeted recess to the full depth thereof, the exposed surface of said surfaced coating layer in said rabbeted recess lying in substantially a common plane with the exposed surface of said surfaced coating layer on the last named row of brick formations.

2. A siding member adapted to be applied to a building wall in interfitted horizontal alignment with like members, comprising a rigid base panel of rectangular configuration having the exposed face thereof coated with asphalt and surfaced with mineral granules of one color along narrow linear portions simulating mortar joints and with mineral granules of a contrasting color along spaced areas simulating brick formations arranged in horizontal rows in staggered order, one longitudinal and one transverse edge of said panel having a ship-lap flange offset with respect thereto, the opposite longitudinal and transverse edges having complementary-formed ship-lap flanges, said first-named longitudinal

edge being defined by a continuously extending mortar joint-simulation, said opposite longitudinal edge having a recess filled with coating and surfaced with granules which extend beyond said edge and define the lowermost edges of the brick formations, thereby serving to effect a tight abutment with the mortar joint-simulation of a vertically adjoining member and conceal the horizontal course arrangement of the horizontally aligned members on a wall.

3. A siding member adapted to be applied to a building wall in interfitted horizontal alignment with like members, comprising a rigid base panel of rectangular configuration having the exposed face thereof coated with asphalt and surfaced with mineral granules of one color along narrow linear portions simulating mortar joints and with mineral granules of a contrasting color along spaced areas simulating brick formations arranged in horizontal rows in staggered order, one longitudinal edge of the panel being defined by a continuously extending mortar joint-simulation, the opposite longitudinal edge having a recess filled with coating and surfaced with granules which extend beyond said edge and define the boundary edge of the brick formations along said last-named longitudinal edge, thereby serving to effect a tight abutment with the mortar joint-simulation of a vertically adjoining member and conceal the horizontal course arrangement of the horizontally aligned members on a wall.

4. A siding member adapted to be applied to a building wall in interfitted horizontal alignment with like members, comprising a rigid base panel of rectangular configuration having a rabbeted recess extending longitudinally on the exposed face thereof along the lower longitudinal margin of the panel, said face and said recess being coated with a layer of asphalt and surfaced with mineral granules, the granules being of one color along narrow linear portions formulating mortar joints and being of a contrasting color along spaced areas simulating bricks arranged in horizontal rows in staggered order, the spaced brick formations in the row immediately adjacent said lower longitudinal margin each having said surfaced coating layer thereon extending into and filling the rabbeted recess to the full depth thereof, the exposed surface of said surfaced coating layer in said rabbeted recess lying in substantially a common plane with the exposed surface of said surfaced coating layer on the last named row of brick formations.

5. A siding member adapted to be applied to a building wall in interfitted horizontal alignment with like members, comprising a rigid base panel of rectangular configuration having a rabbeted recess extending longitudinally on the exposed face thereof along the lower longitudinal margin of the panel, said face and said recess being coated with a layer of asphalt and surfaced with mineral granules, the granules being of one color along narrow linear portions formulating mortar joints and being of a contrasting color along spaced areas simulating bricks arranged in horizontal rows in staggered order, the spaced brick formations in the row immediately adjacent said lower longitudinal margin each having said surfaced coating layer thereon extending into and filling the rabbeted recess to the full depth thereof, and extending slightly beyond the lower edge of the panel, the exposed surface of said surfaced coating layer in said rabbeted recess lying in substantially a com-

mon plane with the exposed surface of said surfaced coating layer on the last named row of brick formations.
